RALPH I. PENDLETON, OF SUNNYVALE, CALIFORNIA

WELL PUMP

Application filed March 30, 1931. Serial No. 526,216.

This invention relates generally to pumps of the gas lift type utilizing compressed gas for elevating water, oil, and other liquids from earth wells. By the term "gas" I have reference to all compressible or elastic fluids, as for example air, or natural gas. In certain respects the invention can be considered an improvement of the invention disclosed and claimed in Pendleton Patent 1,589,551, granted June 22, 1926.

In my aforementioned Patent 1,589,551, I disclosed the use of a gas pump utilizing valve means of the ball check type which is automatically actuated in response to varying fluid pressures to which it is subjected. Movement of the valve ball to one operating position serves to permit inflow of oil from the well into a displacement chamber, while movement of the valve means to the other operating position serves to interrupt flow of oil from the well and effect displacement of the trapped oil towards the surface of the well by gas under pressure. While the pump disclosed in said patent is an operative device and a valuable contribution to the art, in practice it is subject to certain disadvantages. For example under certain operating conditions the ball check will remain in an intermediate position to permit continuous communication between the liquid displacement chamber, and the source of gas under pressure. When this condition prevails proper pumping action does not take place and if the pump is installed in a well in which the oil contains substantial quantities of water, serious emulsification of the oil will result.

It is an object of the present invention to devise a well pump of the above character in which the automatic valve means will properly function under all operating conditions. In this connection the specific form of the invention to be presently disclosed is characterized by the use of separate ball checks for controlling flow of oil from the well into the displacement chamber, and for controlling admission of gas under pressure.

It is a further object of the invention to devise a well pump of the above character which will be characterized by reliability of opera-

tion, in that sand or other foreign material will not tend to render it inoperative.

Further objects of the invention will appear from the following description in which the preferred embodiment of the invention is set forth in detail in conjunction with the accompanying drawings. It is to be understood that the appended claims are to be accorded a range of equivalents consistent with the scope of the prior art.

Referring to the drawings:

Figure 1 is a side elevation in cross section illustrating a pump constructed in accordance with the present invention applied to an oil well.

Fig. 2 is a cross sectional detail taken along the line 2-2 of Fig. 1.

Fig. 3 is a cross sectional detail taken along the line 3-3 of Fig. 1.

Fig. 4 is a cross sectional detail taken along the line 4-4 of Fig. 1.

Referring to the drawings for a detailed description of the modifications shown therein, in Fig. 1 certain parts are shown positioned within an oil well provided with a conventional well casing 10. It is obvious that this casing can be either a casing pipe, a cemented wall, or other equivalent means well known in the art. Extending down into the well from the surface thereof, there is a string of piping 12, which in this particular instance serves as an oil flow passage thru which oil is elevated to the surface of the well. At the lower end of piping 12 there is a special form of coupling 13 which has a threaded connection 14 with the lower section of piping 12, and which has another threaded connection 16 with a pipe section 17. A suitable packing, illustrated diagrammatically at 18, serves to close the space between pipe section 17 and the casing of the well. Thus a space 19 is formed between piping 12 and 17 and the casing of the well, and this space forms a passageway extending down from the surface of the well for flow of a suitable compressed gas.

The interior pipe section 17 forms what can be termed a displacement chamber 21. Coupling 13 is provided with an opening 22 serving to establish communication between

piping 12 and displacement chamber 21. Positioned within displacement chamber 21 there is a valve body 23 which carries various movable valve members as will be presently explained. The lower portion 24 of valve body 23 is in the form of an annular collar, the lower edge of which is seated upon an annular ring 25. Bushing 26 is fixed within collar 24, and serves to form an annular valve seat 27. The intermediate portion of valve body 23 is formed of spaced bars 28 to form what is commonly known as the valve cage. Thus the interior of valve body 23 is in unrestricted communication with the displacement chamber 21. The upper portion 29 of valve body 23 is provided with fluid ports 31, which have communication with the interior of valve body 23 thru annular valve seats 32. The upper end of body portion 29 has a threaded connection 33 with coupling 18, whereby ports 31 are in communication with a port 34, which in turn communicates with space 19.

With respect to the movable valve elements associated with valve body 23, a hollow valve ball 36 is positioned upon the annular seat 27. A plurality of relatively smaller valve balls 37 are associated with the upper annular seats 32. It will be noted that ball 36 is biased by gravity toward closed position, while balls 37 are biased by gravity towards open positions.

Extending upwardly from ball 36 there is an actuating rod 39. The lower enlarged end portion 41 of rod 39 is provided with a lower concave face 42, adapted to fit upon ball 36. The upper end portion 43 of actuating rod 39 is adapted to slidably fit within a guide portion 44 formed within the upper body portion 29. It should be noted that the upper and lower faces of guide portion 44 are sloped away from the actuating rod 39. This is for the purpose of scraping away any accumulation of sediment from rod 39, and also to prevent sand and other sediment from finding its way between guide portion 44 and the cooperating surfaces of actuating rod 39, which might cause the actuating rod to become stuck or inoperative. It will be noted from Fig. 1 that the upper portion 43 of actuating rod 39 is of relatively smaller diameter than the lower portion 46, and that these portions are joined by a conical cam surface 47. When ball 36 is closed upon seat 27, cam surface 47 lies below balls 37, although these balls contact with the portion 43 of the actuating rod. As ball 36 moves upwardly to elevate with it rod 39, cam surface 47 contacts with balls 37, and forces these balls to closed position. When ball 36 is in full operating position, cam surface 47 is at an elevation above the centers of balls 37, as indicated in dotted lines in Fig. 1. Therefore for only an intermediate portion of the movement of ball 36, cam surface 37 effects

movement of balls 37. Furthermore since actuating rod portions 46 and 47 are cylindrical, in both open and closed positions of ball 36, any forces exerted upon balls 37 tending to move these balls toward open position, will not create a component tending to urge actuating rod 39 in a vertical direction. 70

In practice the lower end of pipe section 17 can be connected with further piping 51 which may include an oil strainer or similar means, whereby oil from the well can flow upwardly thru piping 51 and thru annular seat 27, into the displacement chamber 21. When ball 36 is in closed position, it is apparent that such inflow of oil from the well into chamber 21 is interrupted. 75

In many instances it is desirable to provide means which will minimize or prevent carrying of foreign particles into the valve means, together with the gas. For this purpose I have shown a gas strainer 52 connected to coupling 18, and extending upwardly thru the space 19 between casing 10 and piping 12. At some convenient point about coupling 18, strainer 52 is closed with respect to pipe 12, so that compressed gas introduced into space 19 from the surface of the well, is caused to flow thru the perforations of strainer 52, before entering port 34. 80

Operation of my pump can be briefly outlined as follows: Assuming that the device is assembled substantially as shown in Fig. 1 within an oil well, and that the oil in the well tends to seek a level substantially higher than the positioning of ball 36, oil flows inwardly from the well thru annular seat 27, into chamber 21, and seeks a level some point in piping 12 depending upon the natural pressure of the oil in the well. It is also assumed that space 19 is connected at the surface of the well with a substantially uninterrupted source of gas under suitable pressure. During inflow of oil from the well the fluid pressure upon the under side of ball 36 will be greater than the fluid pressure upon the upper side, so that the differential fluid pressure retains ball 36 in open position, above the upper edge of collar 24. While ball 36 is thus retained in open position, balls 37 are closed upon their cooperating seats 32, to prevent introduction of gas under pressure into the displacement chamber. In connection with the differential fluid pressure upon ball 36 it should be noted that there is also a downward component upon actuating rod 39, by virtue of the fact that this rod is exposed to gas pressure in port 34. After a certain head of oil has been attained within piping 12, depending upon the character of the well, ball 36 automatically moves to closed position and a corresponding movement of actuating rod 39 takes place, by virtue of the weight of this rod, and also by virtue of the gas pressure upon the upper exposed end of the same. As this motion 95

takes place, balls 37 move to open position, and gas under pressure is injected into displacement chamber 21, and expansion of this gas displaces or lifts the trapped column of oil. After introduction of gas has continued for a considerable period, it is evident that the differential forces upon ball 36 will vary due principally to two factors, one being the exhausting of gas thru piping 12 to the surface of the well, and the other being the fact that the column of oil above ball 36 has been decreased. Thus eventually the differential forces upon ball 36 will change to such an extent that ball 36 will again move to complete open position, thus interrupting further introduction of compressed gas, and again permitting flow of oil from the well. These operations will occur recurrently and automatically.

It should be noted that balls 37 are not moved to open position before the center of ball 36 has been elevated above the level of the upper edge of collar 24. Since no substantial inflow of oil can occur before the center of ball 36 is raised above the level of the upper edge of collar 24, it is apparent that introduction of gas is interrupted before free inflow of oil is permitted. Likewise inflow of oil is substantially restricted before introduction of gas is permitted. This characteristic of my device insures positive and full movement of ball 36 and actuating rod 39, it tends to prevent introduction of compressed gas into the well, and it also tends to prevent emulsification of the oil.

It is apparent that the invention is susceptible to many modifications and departures from the exact structure disclosed herein. It should be noted particularly that many expedients can be employed for forming separate oil and gas flow passages extending down from the surface of the well. For example piping can be employed for forming a gas flow passage and the space between this piping and the casing of the well can be employed for the flow of oil. Likewise strings of piping can be employed independently of the well casing for forming the oil and gas flow passages, and these strings can be either side by side, or concentric.

I claim:

1. In a liquid well pump of the gas type, piping extending down into the well and serving to form separate gas and oil flow passages, said gas flow passage having communication with a substantially uninterrupted source of gas under pressure at the surface of the well, means forming a displacement chamber within the well which is in communication with the lower portion of the oil flow passage, and valve means associated with said displacement chamber, said valve means including a ball check serving to permit flow of oil from the well into said chamber, a separate ball check serving to con-

trol admission of gas from the gas flow passage into said chamber, and mechanical means interconnecting said checks whereby opening of said first mentioned check effects closing of the second mentioned check, said valve means being automatically actuated by varying fluid pressures to which the valve means is subjected. 70

2. In a liquid well pump of the gas type, piping extending down into the well and serving to form separate gas and oil flow passages, said gas flow passage having communication with a source of gas under pressure at the surface of the well, means forming a displacement chamber within the well which is in communication with the lower end portion of the oil flow passage, and valve means associated with said displacement chamber, said valve means including a ball check serving to permit flow of oil from the well into said chamber but serving to prevent flow of oil from said chamber back into the well, a separate valve member serving to control admission of gas from the gas flow passage into said chamber, and mechanical means interconnecting the ball of said check with said valve member, whereby opening of said ball check effects closing of said valve member, said valve means being automatically actuated by varying fluid pressures to which the same is subjected. 80 25

3. In a liquid well pump of the gas type, piping extending down into the well serving to form separate gas and oil flow passages, said gas flow passage having communication with a source of gas under pressure, means forming a displacement chamber within the well which is in communication with the lower end portion of the oil flow passage, and valve means associated with such displacement chamber, said valve means including a valve member movable to either one of two positions to permit a flow of oil from the well into said chamber or to prevent such flow, a separate ball check serving to control admission of gas from the gas flow passage into said chamber, and mechanical means interconnecting said valve member and the ball of said check whereby opening of said valve member effects closing of said check, said valve means being automatically actuated by varying the fluid pressures to which the same is subjected. 100 105 110

4. In a liquid well pump of the gas type, piping extending down into the well and serving to form separate gas and oil flow passages, said gas flow passage having communication with a source of gas under pressure, means forming a displacement chamber within the well which is in communication with the lower end portion of the oil flow passage, and valve means associated with said displacement chamber, said valve means including a valve member movable to either open or closed positions, and serving when 120 125

- in open position to permit flow of oil from the well into said displacement chamber and when in closed position to prevent such flow and to trap oil in the displacement chamber, 5 a separate movable valve member serving to control admission of gas from the gas flow passage into said chamber, and mechanical means connecting said valve members whereby movement of said first named valve member 10 to open position serves to effect closing of said second mentioned valve member and whereby movements of said first named valve member to closed position serves to effect opening of said second mentioned valve member, said mechanical connection being so arranged that fluid forces upon said second mentioned valve member tending to move the same towards open position do not tend to move said first named valve member towards closed position, for either open or closed position of said first mentioned valve member.
5. In a liquid well pump of the gas type, piping extending down into the well and serving to form separate gas and oil flow passages, said gas flow passage having communication with a substantially uninterrupted source of gas under pressure, means forming a displacement chamber within the well which is in communication with the lower end portion of the oil flow passage, and valve means associated with said displacement chamber, said valve means including a valve member movable between open and closed positions and serving to control flow of oil from the well into said chamber, a separate valve member movable between open and closed positions and serving to control admission of gas from the gas flow passage 25 into said chamber, and mechanical means interconnecting said valve members, whereby opening of said first mentioned valve member serves to effect closing of said second mentioned valve member, said mechanical connection including a cam adapted to effect substantially complete movement of said second mentioned valve members between open and closed positions for an intermediate portion of the movement of said first mentioned 30 valve member, said valve means being automatically and recurrently actuated by varying fluid pressures within the well.
6. In a liquid well pump of the gas type, piping extending down into the well and serving to form separate gas and oil flow passages, said gas flow passage having communication with a substantially uninterrupted source of gas under pressure, means forming a displacement chamber within the well which is in communication with the lower end portion of the oil flow passage, and valve means associated with said displacement chamber, said valve means including a ball check serving to control flow of oil from the well into said chamber, a separate ball check located at an elevation above said first mentioned ball check and serving to control admission of gas from the gas flow passage into said chamber, and mechanical means extending upwardly from the ball of said first mentioned check to the ball of said second mentioned check and serving to effect closing of said second mentioned check upon opening movement of said first mentioned check and vice versa, said valve means being automatically actuated by fluid pressures upon surfaces of the same.
7. In a liquid well pump of the gas type, piping extending down into the well and serving to form separate gas and oil flow passages, said gas flow passage having communication with a source of gas under pressure, means forming a displacement chamber within the well in communication with the lower end portion of the oil flow passage, and valve means associated with said displacement chamber, said valve means including a ball check movable between open and closed positions and serving to control flow of oil from the well into said chamber, a separate ball check movable between open and closed positions and serving to control admission of gas from the gas flow passage into said chamber, said second mentioned check being located at an elevation above said first mentioned check, an actuating rod having its lower end seated upon the ball of the first mentioned check and having its upper end portion extending adjacent the ball of the second mentioned check, and cam means upon said rod serving to engage the ball of said second mentioned check, whereby upon opening of said first mentioned check said second mentioned check is closed while upon closing of said first mentioned check said second mentioned check is opened, said valve means being automatically actuated by varying fluid pressures to which the same is subjected.
8. In a liquid well pump of the gas type, piping extending down into the well and serving to form separate gas and oil flow passages, said gas flow passage having communication with a source of substantially uninterrupted gas under pressure at the surface of the well, means forming a displacement chamber within the well which is in communication with the lower end portion of the oil flow passage, a valve body disposed within said displacement chamber, upper and lower ball seats formed in said valve body, the upper portion of said body being provided with a duct serving to establish communication between the lower portion of the oil flow passage and the interior of the valve body, and the lower portion of the valve body being provided with an opening serving to establish communication between the well and the interior of the valve body, the interior of the valve body being in communication with said displacement chamber.

chamber, a valve ball adapted to cooperate with the upper seat, a substantially larger valve ball adapted to cooperate with the lower seat, a rod having its lower end engaging the lower larger ball whereby said rod is moved upwardly when said larger ball is elevated to open position, means for guiding the upper portion of said rod, and cam means carried by said rod whereby the smaller upper ball is moved to closed position when said rod is elevated by movement of said larger lower ball to open position.

In testimony whereof, I have hereunto set my hand.

15 RALPH I. PENDLETON.
